Primary Examiner — Eric Goodman*Assistant Examiner* — Alyse Joseph(74) Attorney, Agent, or Firm — Cantor Colburn LLP(57) CLAIM

We claim, the ornamental design for a display screen or portion thereof with icon, as shown and described.

DESCRIPTION

FIG. 1 is a front view of a display screen or portion thereof with icon, showing our new design;

FIG. 2 is another front view thereof, as shown in a display screen environment; and,

FIG. 3 is another front view thereof, as shown in another display screen environment.

The broken lines are for environmental purposes only and form no part of the claimed design. The dot-dash broken lines represent unclaimed boundary lines and form no part of the claimed design.

1 Claim, 3 Drawing Sheets(56)
